ILLINOIS.

SAFETY DEVICE FOR SCREW JACKS.

Application filed January 6, 1928. Serial No. 244,859.

This invention relates to safety devices for lifting jacks and particularly for journal jacks which are provided with no geared retarding mechanism, the object of the invention being to prevent the lifting screw, when worn, from turning and accidentally lowering the load.

This object is attained by the mechanism illustrated in the accompanying drawing.

10 For the purpose of illustrating the invention, one preferred form thereof is illustrated in the drawings, this form having been found to give satisfactory and reliable results, although it is to be understood that 15 the various instrumentalities of which the invention consists can be variously arranged and organized, and the invention is not limited to the precise arrangement and organization of these instrumentalities as 20 herein shown and described except as required by the scope of the appended claims.

Of the drawings:

Figure 1 represents a vertical section of a lifting jack embodying the principles of the 25 present invention, and

Figure 2 represents a partial horizontal section on line 2, 2, on Fig. 1.

Similar characters indicate like parts throughout the several figures of the drawings.

In the drawings 10 is a casing having a cylindrical bearing at its upper end in which the standard 11 is adapted to reciprocate, said standard being prevented from turning about its axis by the key 12 secured to casing 10 and projecting into the vertical slot 13 of standard 11.

The lower end of the standard 11 has secured therein a nut 14 coacting with the rotatable steep pitch screw 15, the lower end of which has keyed thereto a bevel gear 16 meshing with another bevel gear 17 formed upon the inner end of a driving shaft 18 revoluble in a bearing in the casing 10 and having an actuating device 19 on the outer end thereof.

The actuating device which preferably is used on this driving shaft 18 is that shown in another application of Frank L. Gormley, filed Dec. 21, 1926 and numbered 156,109 to which reference may be made as to construction and operation.

The gear 16 rests upon a bearing plate or disk 20 superimposed upon a plurality of balls 21 disposed in a circular track formed 55 in the upper face of another plate or disk 22 supported upon the removable bottom 23 of the casing 10.

This bottom member 23 is preferably threaded to the lower part of the casing as 60 indicated at 24.

The threads of the lifting screw 15 in a jack of this character must necessarily have a coarse pitch in order to maintain speed when lifting and lowering and still have the 65 jack compact as otherwise it would be necessary to use gears of much greater diameter if the pitch of the screw threads is reduced.

This would necessitate making the lower end of the casing of greater diameter, thereby increasing the weight of the jack and making it awkward to handle.

Moreover, it would be so bulky that it could not be used in some places, especially 75 in close quarters where there would not be room for the actuating device 19 to be operated to run its standard up to and from the load to be raised.

With this steep coarse pitch of thread in screw and its coacting nut 14 a certain 80 amount of wear takes place between these two member after the jack has been in use some time due to the frictional contact between the contacting screw threads and nut threads.

This is very objectionable for the reason that as the wear increases there is a tendency for the standard 11 having a load thereon to cause the screw 15 to turn and thereby accidentally lower the load.

Some means therefore should be provided in jacks of this character to prevent this accidental lowering and one way of accomplishing this is shown in the drawings.

To this end the plate 20 has an annular 95 peripheral groove 25 formed therein and in this groove 25 is positioned a coil 26 of spring wire having its opposite ends 27 alined and extending outwardly from the coil 26.

These ends 27 are positioned in holes 28 formed in the casing 10 and thus prevent any rotation of the coil 26.

When the spring coil 26 is formed its in-

ner diameter is considerably less than the diameter of the inner wall of the groove 25.

In assembling the spring coil 26 within the groove 25 said coil must be spread open 5 but as soon as it is positioned within the groove 25 it grips the wall of said groove and creates a friction thereon.

This frictional engagement between the spring coil 26 and the wall of groove 25 is 10 considerably less than that of the frictional engagement between plate 20 and gear 16.

Consequently under normal conditions the friction spring 26 is sufficient to prevent the rotation of the main screw 15 even when a 15 load is on the standard 11.

When the actuating device 19 is used to rotate the screw 15 the plate 20 will rotate with the gear 16 overcoming the friction between spring 26 and the wall of groove 25.

20 When the actuating device 19 is not used to rotate the screw 15, the friction between the spring 26 and plate 20 will be sufficient to prevent any rotation of said screw by pressure exerted thereon by the tendency of 25 the nut 14 to move downwardly under the weight of the load upon the standard 11 and this is true even when the screw and nut threads have become well worn.

This friction between the spring 26 and 30 plate 20 is also sufficient to overcome the frictional contact between the ratchet and pawl in the actuating device 19 so that the standard 11 may be raised by short strokes of the actuating device 19.

35 The spring 26 is shown coacting with the periphery of the plate 20 and this is the preferred form but it is quite obvious that said spring may be applied to some other cylindrical member rotating with the main screw 40 15 and accomplish the same results.

It is believed that the operation and many advantages of the invention will be understood without further description.

Having thus described our invention, we 45 claim:

1. In a lifting jack including a casing, a vertically movable standard, and a rotatable member within the casing for moving said standard having an annular peripheral 50 groove; a non-revoluble member within said groove and in frictional contact therewith.

2. In a lifting jack including a casing, a vertically movable standard, and a rotatable member within the casing for moving said 55 standard having an annular peripheral groove; a coiled spring in frictional contact with the bottom of said groove with its ends positioned in holes in the wall of said casing.

3. In a lifting jack including a standard 60 and a rotatable steep pitch screw for raising said standard enclosed within a casing; a cylindrical member rotatable with said screw having an annular peripheral groove; and yielding means supported by said casing and

in frictional contact with the bottom of said 65 groove.

4. In a lifting jack including a standard and a rotatable steep pitch screw for raising 70 said standard enclosed within a casing; a cylindrical member rotatable with said screw; and yielding means supported by said casing coiled about said member and in frictional contact therewith.

5. In a lifting jack including a standard and a rotatable steep pitch screw for raising 75 said standard enclosed within a casing, said casing having oppositely disposed holes in the wall thereof; a cylindrical member rotatable with said screw having an annular peripheral groove; and a yielding coiled 80 spring in frictional contact with the bottom of said groove having its ends disposed in said oppositely disposed holes.

6. In a lifting jack including a standard, a rotatable steep pitch screw for raising said standard enclosed within a casing and having a driving gear keyed thereto; a bearing plate upon which said gear rests having an annular peripheral groove; and a coiled 90 spring supported by said casing in frictional contact with the bottom of said groove.

7. In a lifting jack including a standard, a rotatable steep pitch screw for raising said standard enclosed within a casing and having a driving gear keyed thereto; a bearing 95 plate upon which said gear rests having an annular peripheral groove; and a coiled spring in said groove the normal diameter of which is less than the diameter of said groove and having oppositely extending ends 100 disposed in holes in said casing.

8. In a lifting jack, a casing containing an elevating mechanism consisting in part of a rotatable cylindrical member having an annular peripheral groove; and yielding means supported by said casing and disposed within said groove in frictional contact with the wall thereof.

9. In a lifting jack, a casing containing 110 an elevating mechanism consisting in part of a rotatable cylindrical member having an annular peripheral groove; and a non-revoluble spring coiled round the bottom of said groove and in frictional contact therewith.

10. In a lifting jack, a casing containing 115 an elevating mechanism consisting in part of a rotatable cylindrical member having an annular peripheral groove; and a non-revoluble coiled spring surrounding the bottom 120 of said groove and in frictional contact therewith, the normal diameter of said coiled spring being less than the diameter of said groove.

Signed by us at Harvey, Illinois, this 3rd 125 day of January, 1928.

FRANK L. GORMLEY.
JOHN BULIK.
